ROLL FOR TEXTILE MACHINES

Edwin H. Hansen, Braintree, Mass., assignor to
 Andrews and Goodrich, Inc., Dorchester, Mass.,
 a corporation of Massachusetts

Application June 3, 1941, Serial No. 396,418

3 Claims. (Cl. 28—28)

This invention relates to rolls for use in drying apparatus, warp slashing machines and other textile machines, and the invention may be embodied in a ribbed roll, that is, one which is provided on its exterior with ribs extending longitudinally thereof, or it may be embodied in a roll having a smooth surface.

Sometimes rolls of this type are made with an exterior surface of non-corrosive material, or if the roll is a ribbed roll, the ribs are sometimes made of non-corrosive material.

One known way of making such a roll is to provide a tubular cylinder of a length equal to that of the completed roll and of a diameter approximately that which the roll is to have, and then to cover the cylinder with a sheet metal envelope which is rigidly secured thereto in some suitable way.

If the roll is to have a non-corrosive exterior surface, then this sheet metal envelope is made of non-corrosive material, and if the roll is to have ribs on its exterior, then these ribs may be formed in the sheet metal envelope.

One of the objects of my present invention is to provide a novel roll which may or may not have ribs extending longitudinally thereof and which may or may not have its exterior surface formed of non-corrosive material, but which, nevertheless, will be considerably lighter in weight than a roll of the same size made as above described and which will also be substantially as rigid as a roll formed by covering a tubular body member with a sheet metal envelope.

A further object of the invention is to provide a hollow roll of this type in which the shell is made up of a plurality of strips or sections of sheet metal that are assembled and interlocked together to form the completed roll. If the roll is to be a ribbed roll, then these separate sections may each be preformed with a rib extending longitudinally thereof so that when the sections are assembled to form the shell of the roll, the completed roll will have a plurality of longitudinal ribs on its exterior. If the roll is to have an exterior surface of non-corrosive material, then the sheet metal sections will be made of such non-corrosive material.

Further objects of the invention are to provide various improvements in rolls of this type, which will be more fully hereinafter set forth.

In the drawings, wherein I have illustrated a selected embodiment of my invention:

Fig. 1 is a longitudinal section through a roll which is made in accordance with the invention,

said figure illustrating one embodiment of the invention.

Fig. 2 is a view of one of the interior supporting disks of the roll shown in Fig. 1, said disk being shown on a larger scale than in Fig. 1.

Fig. 3 is a view of one of the end disks of the roll, shown in Fig. 1, said disk also being shown on a larger scale than in Fig. 1.

Fig. 4 is an enlarged sectional view on the line 4—4, Fig. 1.

Fig. 5 is a fragmentary perspective view of one of the preformed sheet metal strips of which the cylinder is composed.

Fig. 6 is a somewhat diagrammatical view illustrative of a slashing machine which is equipped with rolls embodying my invention.

Fig. 7 is a fragmentary perspective view similar to Fig. 5 but showing a different form of sheet metal strip.

Fig. 8 is a cross-sectional view through a cylindrical roll made from strips similar to those shown in Fig. 7.

Fig. 9 is a view of one of the end disks used in the roll shown in Figs. 8 and 10.

Fig. 10 is a fragmentary perspective view of the end of the cylindrical roll shown in Fig. 8.

Fig. 11 is a fragmentary perspective view of a sheet metal strip from which a cylindrical roll having ribs may be formed.

The body portion of my improved roll is made up of a series of sheet metal strips extending longitudinally of the roll, each of which strips is so shaped that it may be interlocked at each edge with an adjacent strip. When a plurality of these strips are assembled with their edges connected together, they constitute the body of the cylinder or roll, and if these strips are made of some non-corrosive material, such as brass or stainless steel, the completed roll will have a non-corrosive surface.

If the roll is to have ribs extending longitudinally thereof, then some or all of the sheet metal strips may be deformed to provide the ribs.

In Fig. 5, there is shown at 1 a preformed sheet metal strip such as may be used in making one form of ribbed roll embodying my invention. This strip is formed from sheet metal which has been deformed to provide the outwardly directed rib 8 which extends longitudinally of the strip from one end to the other, and one edge portion of the strip is bent inwardly to form the inwardly extending wing 9. The other edge of the strip is also bent inwardly, as shown at 10 and then is bent back on itself, as indicated at 11, thereby forming a longitudinal groove or pocket

12 between the portions 10 and 11. This pocket 12 is of a width to receive the wing 9 of an adjacent strip. The wing 9 may be referred to as a "single edge" and the portions 10 and 11 as a "double edge." The inbent single edge and double edge portions 9, 10 and 11 have an angular relation to each other, so that when a plurality of these strips are assembled by inserting the wing or single edge 9 of one strip into the pocket 12 of the double edge of an adjacent strip, the assembled strips will form the shell of the roll.

In the construction herein shown in Figs. 1 to 4, there are twelve of such strips 7 interlocked together to form the surface of the roll, and hence the roll will have twelve ribs 8.

These assembled strips 7 are maintained in their assembled relation by means of disks situated within the roll and which are mounted on a central shaft 13, preferably a tubular shaft. There are two end disks 14, one at each end of the roll, and a plurality of intermediate disks 15, the number of which are dependent somewhat upon the length of the roll. These disks may be polygonal in shape, as shown in Figs. 2 and 3, and thus provided with flat faces 16, or they may be circular in shape, as shown in Fig. 9. If the disks have a polygonal shape, I will preferably make each strip 7 with the two flat or straight sections 17, one either side of the central rib 8, which flat sections 17 have the correct angular relation to each other so that they rest on the two adjacent flat faces 16 of the disks 14 and 15. The intermediate disks 15 are each formed with a plurality of slots 18, there being one slot extending inwardly from the median point of each flat face 16. Each slot 18 is of a size to receive the inbent double edge portion 10 and 11 of a strip 7, and when the disks 15 are assembled with the connected strips 7, the interlocking edges of adjacent strips occupy the slots 18 of the disk 15, as clearly shown in Fig. 4.

The end disks 14 are made to set within the shell of the roll, and in the construction shown in Figs. 1 to 5, they are made without any slots. Hence, in order to accommodate the disks 14, the ends of the inbent portions 9, 10 and 11 are cut away slightly, as indicated at 20 in Fig. 5, the amount which these inbent portions are cut away being substantially equal to the thickness of each end disk 14. When the end disks 14 are in place, therefore, the ends of the flat portions 17 overlie the flat faces 16 of the disks 14, and the inner faces of the disks 14 rest against the edges 20 of the inbent portions 9, 10 and 11.

The end disks 14 are permanently secured in some suitable way to the roll body (which is made up of the assembled sheet metal strips 7), and one convenient way of accomplishing this is by welding the head or end disk 14 to the ends of the sheet metal strips, as indicated at 22.

The end disks 14 are also preferably welded to the central shaft 13, as indicated at 21, and the intermediate disks 15 are also preferably rigidly secured to said shaft 13, as by means of welding.

There is shown in Fig. 1 a plurality of collars 23 mounted on the shaft 13, said collars being welded or otherwise secured to the shaft and forming means for positioning the intermediate disks 15. The roll, when completed, will be provided with trunnion members 24 which are secured to the ends of the shaft 13 or may be made integral therewith, said trunnions providing means for rotatably supporting the roll.

In Figs. 7 to 11 I have shown a roll embodying

my invention having a cylindrical surface rather than a flat-sided surface such as the roll shown in Figs. 1 to 4. In making a roll having a cylindrical surface, the strips, indicated at 7a from which the roll is made, will each be curved transversely on an arc corresponding to the curvature of the cylindrical roll. Each strip 7a is also provided along one side with the inwardly bent single edge or wing 9a, and at the other side with the inwardly bent double edge 10a, 11a, which provides the pocket 12a to receive the single edge 9a of an adjacent strip. These curved strips are assembled in the same way as described with reference to Figs. 1 to 4 to produce the surface of the roll. The end disks 14a and intermediate disks 15a are circular in shape and have a peripheral curvature corresponding to the curvature of the strips 7a so that these strips, when assembled, will fit the peripheries of the disks. Both the end disks 14a and the intermediate disks 15a are provided with radial slots 18a at their peripheries to receive the interlocked edges 9a, 10a, 11a of adjacent strips. These disks 14a and 15a are mounted on a central shaft 13a and are preferably welded thereto. In this construction, the ends of the single edges 9a and double edges 10a, 11a, project through the end disks 14a and come flush with the outer surface thereof. The ends of the strips 7a will preferably be welded to the end disks 14a, and if desired, the adjacent strips may be welded together at their meeting edges, as shown along the seams 21 where the edges of adjacent strips meet.

In Figs. 7 to 10, the strips 7a have smooth exterior surfaces. If it is desired to build a cylindrical roll with ribs extending longitudinally thereof, then I propose to use sheet metal strips 7b such as shown in Fig. 11. These strips are curved the same as the strips 7a shown in Fig. 7, and each strip is bent along one side to provide the single edge 9b and is bent along the other side to provide the double edge 10b, 11b, and to form the pocket 12b.

The curved strip 7b is deformed to present a rib 8a extending longitudinally thereof. A roll made up of the strips 7b, such as shown in Fig. 11, will be a cylindrical roll that has a plurality of ribs 8a extending longitudinally thereof.

The ribbed rolls, such as shown in Figs. 1 to 4, and such as would result from the use of the ribbed strips, shown in Fig. 11, are especially adapted for use in slashing machines for supporting the wet warp threads as they emerge from the sizing bath, and also in other textile machines where a roll is required for supporting wet threads or wet cloth. The presence of the ribs hold the wet threads or wet cloth out of contact with the surface of the roll and thus prevent such wet threads or cloth from sticking to the roll surface.

For use in driers or other textile machinery where the presence of ribs on the roll is not necessary, then the plain surface rolls such as shown in Figs. 7 to 10 may be employed.

A roll embodying my invention is relatively light in weight for its size and is also a very rigid roll. It can be easily manufactured by the assembly method since the various parts of which the roll is made can be readily formed from sheet metal and the assembly of the parts does not involve highly skilled labor.

If it is desired that the roll should have a surface of non-corrosive material, then the strips 7 will be formed from non-corrosive sheet metal, and when they are assembled to make the com-

plete roll, the latter will have a surface of non-corrosive material.

I claim:

1. A roll for textile machines comprising a plurality of sheet metal sections, each extending lengthwise of the roll and each having its longitudinal edges bent inwardly, the inwardly bent portions at the meeting edges of two adjacent sections being interlocked, an end disk fitting within the assembled sections at each end of the roll and secured thereto, a plurality of intermediate disks fitting within the assembled sections, each intermediate disk having radially extending slots at its peripheral portion to receive the interlocked portions of the adjacent sections, and a shaft extending axially through all of said disks and on which the roll is supported.

2. A roll for a textile machine comprising a plurality of sheet metal sections, each extending lengthwise of the roll and each having one longitudinal edge bent inwardly to form an inwardly directed wing and the other longitudinal edge bent inwardly and then bent outwardly to form between the inwardly and outwardly bent portions a pocket to receive the wing of an adjacent section, an end disk fitting within the assembled sections at each end of the roll and secured thereto, a plurality of intermediate disks fitting

within the assembled sections between the end disks, each intermediate disk having radially extending slots at its peripheral portion to receive the interlocked inwardly bent portions of adjacent sections, and a shaft extending axially through said disks and on which the roll is supported.

3. A ribbed roll for a slashing machine comprising a plurality of sheet metal sections, each 10 extending lengthwise of the roll and each being deformed to present an outwardly extending longitudinal rib, each section having one longitudinal edge thereof bent inwardly to form an inwardly directed wing and the other longitudinal edge bent inwardly and then outwardly to form between the inwardly and outwardly bent portions a pocket to receive the wing of an adjacent section, an end disk fitting within the assembled sections at each end of the roll and secured thereto, a plurality of intermediate disks fitting within the assembled sections between the end disks, each intermediate disk having radially extending slots at its peripheral portion to receive the interlocked inwardly bent portions of adjacent sections, and a shaft extending axially through said disks and on which the roll is supported.

EDWIN H. HANSEN.
